UNITED STATES PATENT OFFICE.

JAMES C. DOW, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT-BREAKER.

973,924.

Specification of Letters Patent. Patented Oct. 25, 1910.

Application filed July 13, 1907. Serial No. 383,659.

To all whom it may concern:

Be it known that I, JAMES C. Dow, a citizen of the United States, and a resident of Wilkinsburg, in the county of Allegheny and State of Pennsylvania, have invented a new and useful Improvement in Circuit-Breakers, of which the following is a specification.

My invention relates to automatic circuit interrupters, and it has for its object to provide a device of this class that shall be simple in construction and that shall embody an improved release mechanism.

In the prior art, circuit-breakers have usually comprised release mechanisms in which movable core members were attracted, under predetermined conditions, by stationary core members for the purpose of tripping latches or other holding devices. The weight of the movable core member was sometimes relied upon to oppose, to a greater or less degree, the attraction of the energized stationary core member, but springs have been more generally employed, by reason of the facility with which their tension may be adjusted. The principal difficulty, in a construction of this character, arises from the fact that the pull exerted by the spring is increased as the movable core member approaches the stationary member and, consequently, the tripping action is rendered uncertain and the attractive energy necessary to effect an interruption of the circuit is not clearly defined.

According to my present invention, I employ an improved release mechanism which avoids the difficulties of the prior art by so arranging the movable parts that when a predetermined attractive force is exerted by the stationary core member a well defined action of the movable parts is effected and, consequently, an accurate adjustment may be made.

Figure 1 of the accompanying drawings is a side elevation of a circuit interrupter constructed in accordance with my invention. Figs. 2, 3, 4, 5 and 6 are detail views of the operating and release mechanisms of the device shown in Fig. 1, and Fig. 7 is a view, similar to Fig. 1, of a circuit-breaker having a modified form of tripping mechanism.

Referring to Figs. 1 to 6, inclusive, in which a preferred construction is shown,

the device here illustrated comprises stationary contact members 1 and 2 which are mounted on a stationary slab or switchboard panel 3 of insulating material, a movable bridging contact member 4 and an operating mechanism 5.

The interrupter is equipped, in the usual manner, with arcing contact members 7 and 8 which effect a final break of the circuit when the interrupter opens. The movable contact member 4 comprises a laminated part 6, the beveled ends of which engage the stationary members 1 and 2 when the interrupter is closed, and a holder 9. The holder 9 is rotatably supported upon a shaft 10 by means of a link 11. The operating mechanism 5, of which the link 11 forms a part, is supported by side plates 12 that project from the insulating slab 3 and comprises a handle lever 16 and an operating bell-crank lever 13, the latter being fulcrumed upon a stationary shaft 14 and connected, at one end, to the holder 9 by means of a link 15.

The movable arcing contact member 8 is supported at one end of an arm 17 that is fulcrumed upon a shaft 18 with which the holder 9 is provided and is held in engagement with the stationary arcing contact member 7, when the interrupter is closed, by means of a spring 20 which connects the free end of the arm 17 with a pin projection 21 on the bell crank lever 13.

The release mechanism comprises a magnet winding 22 which is interposed electrically between the stationary contact member 2 and one terminal 23 of the circuit interrupter, a stationary core member 24, a movable core member or armature 25, a latch lever 26 and a tension spring 27. The armature 25 is movably mounted about a shaft 28 which is located considerably below and slightly at one side of its center of gravity, and the arrangement of parts is such that the weight of the armature and the force of attraction exerted by the stationary core member 24 are united in opposition to the spring 27. Movement of the armature 25 is limited in one direction by the stationary core member and may be limited in the opposite direction by any suitably located stop device.

As illustrated in Figs. 5 and 6 of the drawings, the armature 25 is in the form of

a two-part lever comprising side strips 29, the center lines of which are substantially vertical, hub members 30 and a laminated magnetizable cross bar 31 that is secured to 5 the upper ends of the side strips. The strips 29 are of such form that the weight of the laminated member tends to cause movement of the armature, as above indicated. One 10 of the side strips 29 is provided with a forked projection 32 to which the upper end of the spring 27 is attached. The tension of the spring 27 may be adjusted by a thumb-screw 35 and a nut 33.

The latch 26, which is in the form of a 15 bell-crank lever, is mounted upon the shaft 28, between the hub members of the armature 25, and is resiliently connected to the armature by means of a spring 36. The arm 37 of the latch lever 26 is bifurcated 20 and is provided with a roller 38 that may be engaged by a hook projection 39 which extends laterally from one arm of the operating bell crank lever 13 and has a beveled inner end. The rotary movement of the 25 latch lever 26 is limited by a cross-bar 40 of the armature 25.

As the circuit interrupter is closed, the 30 latch lever is raised in opposition to the spring 36 by the engagement of the roller 38 with the beveled surface of the hook projection 39. A pointer 41 projects from the nut 33 and is adapted to indicate, in connection with a suitably graduated plate 42, the current value at which a predetermined tension 35 of the spring 27 may be overcome.

The handle lever 16 is provided with an 40 insulating handle 43 and is illustrated in detail in Figs. 2 and 3. It is fulcrumed upon the shaft 14 and its movement in one direction effects a rotary movement of the operating lever in the same direction by reason of the engagement of the handle lever with a lateral projection 44 with which the operating lever 13 is provided.

45 The operation of the device is as follows: Assuming that the interrupter occupies its closed position, as indicated in the drawings; the release mechanism may be operated in two ways to suddenly effect the disengagement of the contact members and the interruption of the circuit. This result may be accomplished manually by raising the handle 43 and its handle lever 16 until the extremity of the arm 45 engages the upper 50 end of the latch lever 26 and rocks it upon its shaft 28 sufficiently to release the roller 38 from the hook projection 39. As soon as the holding mechanism is thus released, the spring 20, which is under tension when the 55 interrupter is closed, causes immediate separation of the stationary and movable contact members and the interruption of the circuit. A similar result may be effected automatically if the current traversing the 60 winding 22 exceeds a predetermined amount 55

since the stationary core member 24, being thus energized, will effect a rotative movement of the armature 25 in opposition to the spring 27 and its movement will, in turn, effect a movement of the latch lever 26.

Reference may now be had to Fig. 7, in which corresponding parts are indicated by the same reference characters. The stationary and movable contact members are substantially the same as those represented in Fig. 1, but the movable core member or armature of the release mechanism is arranged with its center of gravity below its center of rotative movement. The latch mechanism and the operating levers are 80 adapted to the aforesaid arrangement of the armature. The lower extremity of the operating lever 13^a is provided with a roller 46 and the latch mechanism comprises projections 47, 48 and 49, the first named of 85 which is adapted to engage the roller 46. The movement of the armature 50 produces movement of the latch mechanism by coming into contact with the projection 49 and a similar movement may be effected manually 90 by the engagement of arm 45 on the handle lever 16 with the projection 48. The movement of the latch is limited in one direction by a stop 51 and its movement in the opposite direction is opposed by a spring 52 95 which is connected, at one end, to the projection 47 and at its other end to the stationary stop projection 51.

It will be observed that, in both forms of circuit interrupter illustrated, the spring 27 100 is so arranged relative to the center of rotative movement of the armature that, as these parts operate, the spring is put under tension, but, at the same time, the point of application of the force so exerted is continually moved more nearly into a line which passes through the center of rotative movement and the stationary terminal of the spring. Consequently, although the 105 spring exerts a greater force, its turning moment is not increased in the same proportion and may be decreased, if desired. By this means, a quick and decisive action of the tripping mechanism is effected as soon as the attraction of the stationary core member is sufficient to cause an initial movement of the armature. This result may be more readily obtained by the structure shown in Fig. 1, by reason of the fact that the center of gravity of the armature moves to a 110 greater distance from a vertical line through its center of rotative movement and the moment of the force due to gravitation, which tends to actuate the armature in opposition to the spring, is increased. In this way, the 115 influence of the spring is lessened as the forces which oppose it are increased.

It will be understood that structural modifications may be effected within the scope of my invention, and I desire, there- 120 125 130

fore, that only such limitations shall be imposed as are indicated in the appended claim.

I claim as my invention:

5. In a circuit breaker, the combination with an insulating base plate, stationary and movable contact members, an interposed link, a bell crank operating lever having an inwardly extending hooked projection, and
10 a bell crank latch pivotally supported between the operating lever and the base and adapted to coöperate with the hooked projection of the operating lever in holding the breaker closed, of a release magnet having a

movable core member pivotally mounted co- 15 axially with the latch and resiliently connected thereto, and a handle lever supported coaxially with the operating lever and having a projection adapted either to close the breaker or to engage the latch in releasing 20 the breaker.

In testimony whereof, I have hereunto subscribed my name this 28th day of June, 1907.

JAMES C. DOW.
